DESIGN FOR A COMBINED BILLFOLD, COIN HOLDER, AND KEY CASE

Abraham A. Seamon, Brooklyn, N. Y.

Application May 12, 1947, Serial No. 138,989

Term of patent 7 years

(Cl. D87—3)

To all whom it may concern:

Be it known that I, Abraham A. Seamon, a citizen of the United States of America, residing in Brooklyn, county of Kings and State of New York, have invented a new, original, and ornamental Design for a Combined Billfold, Coin Holder and Key Case, of which the following is a specification, reference being had to the accompanying drawing, forming part thereof.

Figure 1 is a top view of the combined billfold, coin holder and key case in open position showing my design; and

Figure 2 is a perspective view of the combined billfold, coin holder and key case shown in Figure 1 in open position.

Figure 3 is a fragmentary central cross-sectional view of the billfold, taken on line 3—3 in Figure 2.

The back of the combined billfold, coin holder and key case is substantially plain.

I claim:

The ornamental design for a combined billfold, coin holder and key case, as shown and described.

ABRAHAM A. SEAMON.
